CLAIM

The ornamental design for a cleated sole plate, as shown and described.

DESCRIPTION

FIG. 1 is a bottom perspective view of a cleated sole plate showing my new design;

FIG. 2 is a bottom plan view thereof;

FIG. 3 is a front elevational view thereof;

FIG. 4 is a rear elevational view thereof;

FIG. 5 is a right side elevational view thereof; and,

FIG. 6 is a left side elevational view thereof.

The broken line showing of a shoe upper in the figures is merely for illustrational purposes and forms no part of the claimed design.
